UNITED STATES PATENT OFFICE.

FREDERICK W. GORDON, OF HARTFORD, CONNECTICUT.

DISCHARGE-VALVE FOR COMPRESSORS.

SPECIFICATION forming part of Letters Patent No. 713,631, dated November 18, 1902.

Application filed March 17, 1902. Serial No. 98,543. (No model.)

To all whom it may concern:

Be it known that I, FREDERICK W. GORDON, a citizen of the United States, residing at Hartford, Hartford county, Connecticut, have 5 invented certain new and useful Improvements in Discharge-Valves for Compressors, of which the following is a specification.

This invention, pertaining to discharge-valves for compressors, will be readily understood from the following description, taken in connection with the accompanying drawing, which is a vertical longitudinal section of a portion of the cylinder of an air-compressor fitted with my improved discharge- 15 valve.

In the drawing, 1 indicates the compressor-cylinder, 2 its piston, 3 its piston-rod, 4 its cylinder-head, 5 its discharge-chamber, 6 the outlet from the discharge-chamber, 7 a 20 passage through the cylinder-head placing the compressor-cylinder in communication with the discharge-chamber, all of the parts thus far referred to being of ordinary construction and subject to ordinary and proper 25 modifications; 8, the discharge-valve disposed within the discharge-chamber and seating in the passage 7 and opening toward the discharge-chamber; 9, the stem of the valve projecting outwardly through the outer wall 30 of the discharge-chamber; 10, a rocker fitted on the discharge-chamber and having one end connected with valve-stem 9; 11, a tappet-stem extending through the discharge-chamber parallel with the axis of the compressor, 35 its outer end being connected with rocker 10 and its inner end projecting into the compressor-cylinder in position to be in contact with the compressor-piston when the latter is at the end of its stroke and valve 8 is closed 40 and adapted as valve 8 opens to project still farther into the compressor-cylinder; 12, a valve-piston supported by the discharge-chamber concentric with valve-stem 9; 13, a valve-cylinder formed upon the back of the 45 discharge-valve and fitting valve-piston 12 with proper air-tightness, and 14 a tube surrounding tappet-stem 11 to prevent leakage around the stem from the discharge-chamber.

Assume the compressor to be working and 50 the discharge-chamber to be under pressure and that the parts are in the position indicated in the drawing, the discharge-valve 8

being closed and the compressor-piston ready to begin its suction-stroke to the right. As the compressor-piston moves to the right, the 55 air of suction following it through the usual inlet-valve, (not shown,) discharge-valve 8 is held closed by discharge-pressure upon its back preponderating over suction-pressure upon its front. Under these conditions the 60 compressor-piston completes its stroke to the right and reversing begins its compressive stroke, the pressure in the compressor-cylinder constantly rising as the compressor-piston advances. Cylinder 13 is full of air under at- 65 mospheric pressure, due to leakage-way past stem 9, and consequently the pressure in the discharge-chamber is acting upon only that annular portion of the valve exterior to piston 12 or on an area represented by that of the 70 valve minus that of piston 12. When the increasing pressure in the compressor-cylinder reaches that point at which it acting on the inner face of the valve will preponderate over the discharge-pressure acting on the 75 back of the valve plus atmospheric pressure in cylinder 13, acting on the back of the valve, then the valve will suddenly fly open, the air trapped in cylinder 13 acting as a cushion, but soon leaking out, so that the cushioning- 80 air becomes reduced to that of the atmosphere. The areas of the valve and piston 12 may be so proportioned that this sudden opening of the valve will take place when compression reaches the discharge-pressure or 85 so that it will anticipate it. The valve having suddenly opened remains full open while the compressor is discharging into the discharge-chamber, tappet-stem 11 having protruded into the compressor-cylinder when the valve 90 opened. When the compressor-piston nears the end of its compressive stroke, it makes contact with the inner end of the tappet-stem and gives the valve a movement of closure, the valve being practically closed when the compressor-piston shall have reached the end of 95 its stroke and closing with positive certainty and completeness under the influence of discharge-pressure upon its back when the compressor-piston begins its suction-stroke. 100 The leakage of air from cylinder 13 may be provided for by a little extra looseness of stem 9 in its bearing or by any equivalent arrangement, and the general disposition of es-

sential parts is manifestly subject to numerous constructional modifications without departure from the invention.

I claim as my invention—

5 1. In discharge-valves for compressors, the combination, substantially as set forth, with a compressor-cylinder, compressor-piston, discharge-chamber, and discharge-valve opening to the discharge-chamber, of a piston and cylinder disposed at the back of the discharge-valve and arranged to detract from the area thereof subject to discharge-pressure, a tappet projecting into the compressor-cylinder and adapted to be engaged by the 15 compressor-piston as it nears the end of its compressive stroke, and connections between said tappet and the valve whereby the movement of the tappet under the influence of the compressor-piston causes the practical closure of the valve.

2. In discharge-valves for compressors, the combination, substantially as set forth, with a compressor-cylinder, compressor-piston, cylinder-head, discharge-chamber at the cylinder-head, and discharge-valve disposed 25 within the discharge-chamber and closing toward the compressor-cylinder, of a piston fixed within the discharge-chamber and projecting toward the discharge-valve, a cylinder engaging said fixed piston and connected 30 with the valve, a valve-stem, a tappet-stem projecting into the compressor-cylinder and adapted to be engaged by the compressor-piston as it completes its compressive stroke, and a pivoted rocker connected with the 35 valve-stem and tappet-stem.

FREDERICK W. GORDON.
